2 Sheets-Sheet 1

Fig. 1.

Fig. 1 shows a top-down view of a book binding mechanism. A central spine area is labeled 'M'. On the left, a page block is held by a binding device with components labeled 1, 2, 3, 4, 6, 10, 12, 13, 14, 15, and 16. On the right, another page block is shown with components labeled 9, 10, 11, and 12. The spine area 'M' is labeled with '10' and '11'.

Fig. 2.

Fig. 2 is a detailed view of the binding mechanism. It shows a central spine area with components labeled 1, 2, 3, 4, 5, 6, 7, 10, 13, 14, 15, 16, 17, 18, 19, 20, and 20. The spine area is labeled with '10' and '11'.

Fig. 3.

Fig. 3 shows a side view of the binding mechanism. It features a central spine area with components labeled 1, 2, 3, 4, 5, 6, 7, 8, 9, 10, 11, 12, 13, 14, 15, 16, 17, 18, 19, 20, and 21. The spine area is labeled with '10' and '11'.

Atty.

UNITED STATES PATENT OFFICE

WILLIAM DANA SEIBERT, OF BROOKLYN, NEW YORK

BINDER FOR MAGAZINES, PAMPHLETS, AND OTHER PUBLICATIONS

Application filed December 9, 1931. Serial No. 579,925.

The object of my invention is to provide a binder of novel construction which can be expanded from time to time to hold additional copies of a magazine or other publication 5 regardless of the difference in the thickness of the various issues and which will always present a neat appearance even though it has only one periodical in it or if it has a dozen or more.

It is also an object of my invention to provide a novel spring holder for holding periodicals without necessitating the punching of holes in them or otherwise injuring the periodicals in any way; and to provide a holder 15 which is readily inserted and removed from the magazine.

It is also my object to provide a binder of this type having stiff covers and to provide the novel combination of an arrangement of 20 parts hereinafter described and illustrated in the accompanying drawings, in which—

Figure 1 is a perspective view of my invention in open position, with magazines in place in the binder;

Fig. 2 is a front plan view of the inside of the binder, with the publications removed therefrom;

Fig. 3 is a section on line 3—3 of Fig. 2;

Fig. 4 is a front plan view of the flexible 30 inner binder with straps attached;

Fig. 5 is a section on line 5—5 of Fig. 4;

Fig. 6 is a perspective view of one of the stiff covers or book backs of the binder removed from the rest of the device;

Fig. 7 is a section on line 7—7 of Fig. 6; and

Fig. 8 is a detail perspective view of one of the wire binder members.

Like characters of reference designate like parts in each of the several views.

Referring to the drawings, I provide a flexible inner binder comprising the outer flexible strip 1 and the inner flexible strip 3 fastened to the outer strip by the eyes 4 and by the lines of stitching 5 at each end as shown in Figs. 4 and 5 and having a hinge portion 2. Attached to the opposite ends of the flexible binder strips 3 and 1 are long 45 flexible straps 6 of fabric or other suitable

material secured by suitable means as by the lines of stitching 7.

I provide stiff cover members as shown in Figs. 6 and 7 comprising the inner stiff sheet 55 or cover member 10 and the outer stiff sheet 58 or cover member 9, the member 9 having flap ends 12 glued on to member 10 whereby members 9 and 10 are substantially continuous at the ends, as shown in Fig. 6. I provide a short flexible strap 13 looped over the edge 60 of and fastened at 14 to the inner stiff cover member 10 and carrying a buckle 15 on its free looped end, as shown in Figs. 6 and 7.

I provide a novel spring binder wire 16 having an angularly bent portion 17 to permit the extension of that side and of readily grasping and operating the binder wire to secure a periodical in place in the binder or to release it therefrom. The angularly bent portion also functions to give a spring to the one side so that the book can be easily inserted and held in place between the portions of the wire by the eye 22. The binder wire 16 has a U-shape bend at 19 and its portion 20 is adapted to be inserted in the space 8 between flexible strips 1 and 3 as shown in Figs. 2 and 3. It is bent at right angles at 21 and terminates in a loop or eye 22 which is adapted to be engaged by the opposite hook end 18 as shown in Figs. 1 and 2.

In use the tab of the buckle 15 on the inside of the stiff cover is raised to an upright position to loosen the strap 6 which passes through the buckle as shown in Fig. 85. 2. The stiff cover members 9 and 10 can then be pushed out an inch more or less depending on how much the strap is loosened. The portion 20 of the binder wire is inserted through the space 8 at the hinge portion 2 between 90 flexible binder members 1 and 3, the other half of the binder wire being inserted through the center of the periodical and its hook end 18 engaged in the eye or looped end 22 of the binder wire thus securing the magazine in the binder. The stiff cover members 9 and 10 are then slid up against the publication and the strap 6 tightened in the buckle 15 to secure the magazine in place 95 in the binder. The stiff cover members 9 100

and 10 are open at the sides leaving free space 11.

What I claim is:—

- 5 1. In a binder for periodicals, pamphlets and the like, the combination of strips of flexible material secured together at the ends and having a free space between the strips along the middle portion, flexible long straps attached to the ends of the aforesaid flexible strips, stiff cover members, each of which is formed of two stiff sheets, said sheets being fastened together at the ends and open at the sides to permit the insertion of the flexible binder strips in the spaces between the respective stiff sheets of the cover members, a short strap affixed to the inside stiff sheet of each cover member, each short strap having a buckle adapted to be engaged by the corresponding long strap of the flexible strip, and binder wires engaging around an element of the hinge portion of the binder, each of said wires being adapted to releasably engage magazines.
- 10 2. In a binder for periodicals, pamphlets and the like, the combination of a flexible binder element, said binder element comprising two flexible strips secured together at their ends only, hollow stiff cover members into which the flexible binder element is insertable, the central portion of the flexible binder element forming the hinge portion of the binder, and means inserted between the members of the flexible binder element and carried by said hinge portion to releasably engage a magazine to hold same in the binder, and straps attached to opposite edges of the flexible binder element for securing same in place within the respective hollow stiff cover members.
- 15 3. In a binder for periodicals and other publications, the combination of a flexible binder element, stiff cover members each of which is formed of two stiff sheets, said sheets being fastened together at the ends and open at the sides to provide a space into which the flexible binder element is insertable, the central portion of the flexible binder element forming the hinge portion of the binder, means carried by said hinge portion to releasably engage a magazine to hold same in the binder, straps attached to the flexible binder element for securing it in place within the space between the stiff sheets of the respective stiff cover members, a short strap affixed to the inside stiff sheet of each cover member, these straps carrying buckles engageable by the straps fastened to the flexible binder element to releasably secure same within the stiff cover members.
- 20 4. In a binder for magazines, pamphlets and other publications, the combination of strips of flexible material secured together at the ends and having a free space between the strips along the middle portion, a flexible strap attached to the end of one of the aforesaid flexible strips, stiff cover members, one of said cover members being formed of stiff sheets, said sheets being fastened together at the ends and open at the sides to permit in-
- 25 5. In a binder for magazines, pamphlets and other publications, the combination of a flexible binder element, hollow stiff cover members each composed of two stiff sheets open at the sides and closed at the ends, and between which the flexible binder element is insertable, the flexible binder element forming the hinge portion of the binder, binder wires each having one portion thereof engaging around an inner binder element of the hinge portion of the binder and having the other portion thereof insertable through the magazine to hold same, the said binder wires each having an eye formed at one end and a hook formed at the other end to releasably engage each other.
- 30 6. In a binder for magazines, pamphlets and other publications, the combination of a flexible binder element, stiff cover members each formed of two sheets having a space therebetween to receive a flexible element, said cover members being closed at the ends and open at the sides, the central portion of the aforesaid flexible binder element forming the hinge portion of the binder, spring binder wires each having one portion thereof engaging around an inner binder element of the said hinge portion of the binder and having the other portion thereof insertable through the publication to hold same in the binder, the said binder wires each having an eye formed at one end and a hook formed at the other end to releasably engage each other, the binder wires each also having an angularly bent-out portion to permit of greater flexibility of the binder wire and to facilitate grasping same to unhook the hooked end of the wire from the eye at the other end to insert the wire into or to release it from a publication.
- 35 7. In a binder for periodicals, pamphlets and the like, the combination of strips of flexible material secured together at the ends and having a free space between the strips along the middle portion, a flexible strap attached to the end of one of the aforesaid flexible strips, stiff cover members, one of said cover members being formed of stiff sheets, said sheets being fastened together at the ends and open at the sides to permit in-

sertion of the flexible binder strips in the spaces between the respective stiff sheets of the cover member, a short strap affixed to the inside stiff sheet of the cover member, a buckle on said strap, and binder wires engaging releasably around an element of the hinge portion of the binder and adapted to engage magazines, said binder wires being of a length slightly exceeding that of the magazines engaged by the wires.
